Application December 20, 1940, Serial No. 371,042

3 Claims. (Cl. 261—41)

This invention relates to carburetors for internal combustion engines, and more particularly to an auxiliary carburetor designed to be used in conjunction with the usual or main carburetor.

An object of the invention is to provide an internal combustion engine with a main and an auxiliary carburetor, both delivering into the same intake manifold, and having throttle valves so constructed and connected that first one and then the other of the carburetors are successively brought into action as the accelerator pedal is operated.

A further object is to provide an arrangement of the kind above mentioned in which the auxiliary carburetor has air passages which are relatively small, as compared with those of the main carburetor, and in which the auxiliary carburetor is brought into action first, as the pedal is depressed, whereby, at low engine speeds, air is drawn through said auxiliary carburetor at high velocity, and efficient atomization thus obtained.

A further object of the invention is to provide main and auxiliary carburetors of the character above described, and of the spray nozzle, constant level type, both having jets fed from the same float chamber.

A still further object is to provide an auxiliary carburetor in the nature of an attachment which can be readily applied to existing engines, and to this end the invention contemplates equipping the auxiliary carburetor with an "adapter" constructed to be interposed between the main carburetor and the intake manifold, and serving to connect the auxiliary carburetor with such manifold.

As is well known, it is an inherent characteristic of carburetors of the spray nozzle and Venturi type that, as the engine speed increases, the rate at which fuel is drawn in increases faster than the rate at which air is drawn in, with the result that the mixture tends to become too rich. Various means have heretofore been proposed to overcome this, among such means being what is known as an "air-bled" fuel jet. Still another object of the present invention, therefore, is to produce a more efficient compensating carburetor of the air-bled type, and to this end I provide improved means whereby the amount of air admitted to the jet tube progressively increases with engine speed until the amount needed by the jet is reached.

With the above and other objects in view, and to improve generally on the details both of the

auxiliary carburetor itself and the means by which it is caused to cooperate with the main or conventional carburetor, the invention consists in the construction, arrangement and combination of parts hereinafter described and claimed, and illustrated, by way of example, in the accompanying drawings, forming part of this specification, and in which:

Fig. 1 is a side elevation showing my improved auxiliary carburetor in position between the main carburetor and intake manifold;

Fig. 2 is a plan view of the upper part of the auxiliary carburetor, showing the means for connecting the same to the float chamber of the main carburetor;

Fig. 3 is a plan view of the lower portion of the auxiliary carburetor, showing the "adapter."

Fig. 4 is a longitudinal section substantially on the line 4—4 of Fig. 1, looking in the direction of the arrow;

Fig. 5 is a fragmentary longitudinal section substantially on the line 5—5 of Fig. 2, looking in the direction of the arrows, but on a greatly enlarged scale; and

Figs. 6 and 7 are fragmentary side elevations of the lower portion of the assembly shown in Fig. 1, illustrating the throttle valves in different positions, parts in Fig. 6 being broken away, and parts being shown in section.

Referring to the drawings in detail, A designates what I shall call the main carburetor, this being shown in light lines in Fig. 1 for the sake of clearness, and comprising the usual conventional or any suitable standard type of carburetor. As illustrated, it comprises a tubular body having an intake opening at the upper end 1, and containing the usual mixing chamber and spray nozzle or fuel jet fed from a suitable float chamber 2, to which fuel is supplied through the pipe 3.

4 designates the choke valve lever and this is suitably connected with a lever 5 pivoted at its lower end and carrying an adjustable throttle stop screw 6.

The throttle valve itself is indicated in dotted lines at 12, and this is carried by a shaft 11 journaled in the carburetor body. Secured to this shaft is a set of crank arms 7, 8 and 9, the arm 7 cooperating with the stop screw 6 to limit the idling position of the throttle valve, and the arm 8 having means attached thereto by which the throttle may be operated. Pivotedly connected to the arm 9 is a link 10, connected at its upper end with the usual accelerator pump.

At its lower end, the carburetor A is formed

with a bolting flange A' adapted to mate with and be secured to a similar flange D' at the end of the usual intake manifold D.

While I have shown and described the main carburetor A as comprising certain details of construction, it will, of course, be understood that, so far as the present invention is concerned, the exact details of this carburetor are immaterial.

My improved auxiliary carburetor is designated 10 in its entirety by the reference character B and comprises a tubular body and a laterally extending delivery conduit terminating in an "adapter" C. As shown in Fig. 1, this "adapter" is constructed to be interposed between the flanges A' and D', as will be hereinafter more fully described.

Adapted to engage the usual ball at the end of the actuating arm 8 is a socket member 13 carried by a rod 14 having a head 15 at the opposite end and freely slideable through a pin 17 journaled in a boss 17a carried by an arm 18, secured to a shaft 19 journaled in the body of the auxiliary carburetor. A helical spring 16 surrounds the rod 14 and is interposed between the socket member 13 and pin 17, for a purpose hereinafter described.

Carried by the shaft 19 is a throttle valve 22 controlling the flow of the fuel mixture from the auxiliary carburetor. Carried by the arm 18 is a ball connection 23, to which is pivotally secured the end of an operating rod 24, by means of which the throttles are actuated, as herein-after described, such rod being usually connected with the accelerator pedal.

Referring to Figs. 1, 3 and 4, it will be seen that the auxiliary carburetor B has an air intake at its upper open end 21, and a delivery conduit 25 at its lower end. This conduit extends laterally at substantial right angles to the body of the carburetor, and terminates in the "adapter" C. It will be understood that this "adapter" has a periphery conforming with the shape of the flanges A' and D', and that it is hollow, having an upper wall 26 and lower wall 27, provided with flat outer faces. The central part of the "adapter" is cut away as at 28 to form an opening of substantially the same shape as the end of the manifold D, and the "adapter" is also provided with a plurality of peripheral holes 29 so placed as to register with the bolt holes in the mating flanges A' and D'. While, as shown in Fig. 3, the "adapter" is of somewhat elliptical shape, it may, in many cases, be circular, and the "adapter" may thus properly be described as "annular," this term being intended to include both circular and non-circular configurations.

Thus the "adapter" C, constituting the end of the laterally extending delivery conduit 25, and having opposed flat faces as described, may readily be interposed between the flanges A' and D', as shown in Fig. 1, and the several parts of the assembly rigidly secured together as by means of bolts 30 passing through the aligned bolt holes.

It will thus be seen that by the construction above described, I have provided an auxiliary carburetor in the nature of an attachment which may be readily applied to an existing internal combustion engine, and having an "adapter" which may be interposed between the bolting flanges of the usual carburetor and intake manifold. In actual practice, it will, of course, be necessary to make up the auxiliary carburetors with "adapters" of different shapes and sizes to fit different models of engines. However, having provided the auxiliary carburetor with an "adapt-

er" of the proper shape to fit a particular model of car, it will be seen that the auxiliary carburetor can be readily applied to any car of that model, by disconnecting the existing carburetor from the intake manifold, and interposing the "adapter" between them.

It will be observed from an inspection of Fig. 1 that the auxiliary carburetor, comprising the body and the laterally extending delivery conduit, constitutes a substantially L-shaped structure and that when applied to the engine, the body of the auxiliary carburetor is closely spaced from and parallel with the main or existing carburetor. As illustrated, both carburetors are of the down-draft type.

Referring to the construction of the auxiliary carburetor itself, it will be seen, by reference to Figs. 1 and 4, that it comprises a lower section 20, preferably formed integral with the conduit 25, and an upper section 33 detachably secured thereto as by means of a set screw 32. The upper section 33 is formed integral with or brazed to a Venturi-shaped member 31, having a flange fitting within the section 20, against which flange the set screw 32 bears. Other details of construction may, of course, be employed without departing from the spirit of the invention.

Supported centrally within the tubular upper section 33 of the carburetor is a venturi 34, of the usual or any desired shape, adapted to receive the incoming air at its upper funnel-shaped end. Projecting into the throat of this venturi is the end of a jet tube 35, constituting a spray nozzle.

In order to break up and more thoroughly vaporize and heavier particles of fuel passing downwardly from the fuel jet, I preferably place in the lower end of the venturi 34 a conical baffle 36, formed of wire netting or other foraminous material, as shown in Fig. 4. It will be noted that this baffle projects down into the throat of the venturi 31, so that not only does the primary air coming down through the venturi 34 and carrying the fuel particles impinge against it, but also the secondary air coming in around the venturi 34 sweeps over it as the air passes down through the venturi 31. Thus the fuel is effectively vaporized.

As illustrated in the drawings, a casting 37 surrounds the upper portion of the tubular section 33 and is formed at one side with a hollow boss 38 constituting a fuel well 39 (see Fig. 4). From the well 39, a port 40 communicates with the jet tube 35.

Seated against the top of the boss 38 is the head 41 of a specially constructed screw member having a shank 42 extending down through the well 39. This member is provided at its lower end with screw threads engaging with similar threads in a cup-shaped fitting 43. An annular spacer or sleeve 44 is shown as interposed between the boss 38 and fitting 43, and it will be seen that when the head 41 is turned, the parts 43 and 44 will be drawn firmly against each other and against the lower surface of the boss 38, thus forming a liquid tight assembly.

By reference to Figs. 1 and 2, it will be seen that a tube 45 taps the cup-shaped fitting 43 and carries at its other end an annular fitting 46, adapted to be clamped by means of a screw 47 to an opening in the bottom of the float chamber 2. Thus the auxiliary carburetor is supplied with fuel from the existing float chamber 2, through the tube 45. In other words, both the main and auxiliary carburetors are fed from

the same float chamber, and the fuel jets are substantially at the same level.

Referring again to Fig. 4, it will be seen that the shank 42 is smaller than the interior of the sleeve 44, so that an annular passage is formed between them, and extending downwardly from this annular passage through the threaded lower end of the shank 42 is a port 48 establishing communication between the well 39 and the cup-shaped fitting 43 into which fuel is delivered by the tube 45.

In order to restrict the flow of fuel up through the passage 48 to the well 39, I preferably place in the lower end of the shank 42 at a point substantially below the intake end of the jet tube, and below the level of the fuel in the well, a removable metering plug 49, having a restricted passage therethrough. It will be understood that a plug having a passage of any desired size to suit the particular conditions may be employed.

The operation of my improved apparatus as so far described will now be briefly explained.

With the parts in the position shown in Fig. 1, the throttle 22 of the auxiliary carburetor is substantially closed, and the spring 16 compressed, thus holding the throttle 12 of the main carburetor in the closed or idling position indicated. In other words, at this time the auxiliary carburetor is inoperative and the fuel required for the engine when idling is provided by the main carburetor, as usual.

When it is desired to operate the engine at working speed, the driver depresses the accelerator pedal and thus exerts a pull on the rod 24. Fig. 6 illustrates the position of the parts when the engine is operating at comparatively low speeds, requiring only a part of the capacity of the auxiliary carburetor. In this figure, it will be seen that the throttle 22 of the auxiliary carburetor is about $\frac{2}{3}$ open, while the throttle 12 of the main carburetor is still maintained in idling position by the spring 16. Thus, under these circumstances, practically all of the fuel for running the engine is derived from the auxiliary carburetor. It will be noted by reference to Figs. 1 and 3 that the cross sectional area of the air passages of the auxiliary carburetor are relatively small as compared with those of the main carburetor, so that, even at low engine speeds, the air flows through the mixing chamber of the auxiliary carburetor at relatively high velocity. This produces efficient atomization of the fuel from the spray nozzle, because a larger proportion of the total volume of air passes close thereto. Owing to the relative sizes of the air passages in the two carburetors, it will be understood that even at low engine speeds the velocity of air through the auxiliary carburetor, which is the only one then supplying any substantial amount of fuel, is of the same order as the velocity of air would normally be through the main carburetor at the highest engine speeds, and thus high efficiency at low engine speeds is obtained.

Fig. 7 shows the position of the parts when the accelerator pedal is still further depressed and the engine is operating at its maximum speed. Here it will be seen that, the spring 16 having expanded to its full extent, and the pin 17 having engaged the head 15, the rod 14, connecting the two throttle mechanisms, has moved the throttle 12 of the main carburetor to substantially full open position, while the throttle 22 of the auxiliary carburetor is also approach-

ing full open position. Thus at high engine speeds, both carburetors are working and both deliver fuel mixture into the intake manifold at substantially the same point. Thus, if there should be an inequality between the character of the mixtures delivered by the two carburetors into the manifold, these two fuel mixtures have an opportunity to blend into a uniform mixture in the manifold before reaching the intake valves.

Referring again to Figs. 6 and 7, it will be noted that the throttle 22 of the auxiliary carburetor occupies somewhat different angular positions in the two figures, Fig. 6 showing it as it begins to move to open position. When the operating rod 24 is moved slightly further to the left than shown in Fig. 6, the throttle 22 will reach substantially full open position, while the throttle 12 still remains in idling position, and it is only after the capacity of the auxiliary carburetor is reached and the operating rod is moved beyond this point that the main throttle 12 begins to open. Finally, when the accelerator pedal is fully depressed, both throttles are wide open, as shown in Fig. 7.

As is well known, it is an inherent characteristic of carburetors of the venturi and fuel jet type that, as the velocity of air increases, the amount of fuel sprayed increases at a greater rate than the air, with the result that the mixture tends to become too rich.

Owing to the extremely high velocity at which air is drawn through my improved auxiliary carburetor at high engine speeds, the fuel mixture which would be produced by this carburetor, as above described, would be far too rich and its efficiency greatly lowered. In order to remedy this defect, I provide a novel compensating arrangement illustrated in detail in Fig. 5.

By reference to Figs. 1 and 2, it will be seen that formed integral with the casting 37 on either side of the boss 38 are vertically disposed cylindrical bosses 50 and 51, and that at the sides of these bosses are other and smaller parallel bosses 52 and 53.

Referring to Fig. 5, it will be seen that longitudinal bores 54 are formed in the bosses 52 and 53, and horizontal bores 55 extend from the bores 54 into the bosses 50 and 51. These bosses 50 and 51 are bored to form valve chambers 57 and 58, and each of these valve chambers communicates at its bottom through a port 56 with the bores 55.

In the chambers 57 and 58 are weighted valves 59 and 60, each having a conical point 61 received in a tapered seat at the upper ends of the ports 56, the weight on one of the valves, as for example the valve 60, being substantially greater than the weight on the valve 59. The upper ends of the chambers 57 and 58 are closed by plugs 62, through which are threaded stop screws 63 adapted to engage the upper ends of the valve members 59 and 60, and limit their movement.

Ports 64 connect the valve chambers 57 and 58 with the fuel well 39. The upper ends of the air passages 54 are closed by means of screw plugs 65 having restricted openings 66 therethrough, for the purpose of limiting the amount of air which can enter.

The operation of this part of the invention is as follows. At low engine speeds, when the velocity of air through the venturi 34 is only moderate, fuel is sucked up through the tube 35 to the jet in the usual manner, the weighted

valves 59 and 60 remaining on their seats. As, however, the engine speed, and hence the velocity of air through the venturi increases to a certain point, a stronger suction is generated in the tube 35 and in the fuel well 39. Since, however, the amount of fuel that can flow to this well is limited by the restricted opening 49 in the metering plug, a partial vacuum is created in the well 39 and this, operating through the port 64, eventually becomes sufficient to lift the lighter valve 59 from its seat. When this happens, air is drawn in through the passages 54 and 55, and port 56, into the valve chamber 57, and this air passes through the port 64 and mixes with the liquid fuel as it enters the port 40 and jet tube 35, thus diluting the fuel and limiting the amount which is actually delivering from the jet.

As the engine speed and suction still further increase, the partial vacuum generated finally becomes strong enough to also lift the heavier valve 60 from its seat, and additional air then enters the valve chamber 58 and flows through the port 64 into the fuel well 39, thus further diluting the fuel supplied to the jet, and further reducing the actual amount delivered.

In this way, I am enabled to compensate for the tendency of the mixture to become unduly rich at higher engine speeds and to produce a mixture which is substantially uniform, for all practical purposes, within the usual speed ranges. While I have indicated the use of only two weighted valves, it will, of course, be understood that a greater number can be employed if desired, and while I have described the valves as weighted, it is apparent that they can, instead, if desired, be operated by springs of progressively increasing strengths. It will also be understood that it is necessary, for the best results, to have the proper relation between the restricted opening in the metering plug 49 and the restricted openings 66 in the air plugs 65, and for this reason these plugs are made removable and interchangeable so that plugs having openings of the proper size may be selected.

What I claim is:

1. The combination with an internal combus-

tion engine having an intake manifold formed with a bolting flange at its end, of main and auxiliary carburetors of the constant level type, each formed as an independent unit, separable from the other and each having a separate mixing chamber and fuel jet, a single, common float chamber with which the fuel jets of both carburetors communicate, means for supplying fuel to said float chamber, said carburetors having superposed portions both connected to the bolting flange of said manifold, a separate throttle valve for controlling the flow of fuel mixture from each carburetor to said manifold, and means for opening said throttle valve successively.

2. An attachment for internal combustion engines having an intake manifold provided with a bolting flange, and the usual carburetor adapted to be connected thereto and having a throttle valve and a float chamber, said attachment comprising an auxiliary carburetor having a fuel jet and throttle valve and also having a laterally extending delivery conduit constructed to fit upon and be secured to said bolting flange and interposed between said manifold and usual carburetor, said attachment also comprising means for connecting the fuel jet of said auxiliary carburetor to the said float chamber, and means connecting the throttle valve of said auxiliary carburetor, to that of the usual carburetor whereby both said valves may be operated by the usual control device.

3. In a carburetor, the combination with a venturi and jet conduit, of a fuel well with which said jet conduit communicates, a float chamber, means including an element having a restricted passage, connecting said well and float chamber, an air inlet passage communicating with said well, a removable plug in said passage having a restricted port therethrough, and an inwardly opening check valve, biased to closed position, independent of said plug and located between the same and said jet conduit and controlling the flow of air through said passage.

45

RALPH SHIPMAN.
